UNITED STATES PATENT OFFICE.

GEORGE L. THOMPSON, OF CHICAGO, ILLINOIS.

COMBINED COMB AND CURLING-IRON.

SPECIFICATION forming part of Letters Patent No. 404,129, dated May 28, 1889.

Application filed December 20, 1888. Serial No. 294,187. (No model.)

To all whom it may concern:

Be it known that I, GEORGE L. THOMPSON, of Chicago, in the county of Cook and State of Illinois, have invented certain new and 5 useful Improvements in a Combined Comb and Curling-Iron; and I do hereby declare that the following is a full, clear, and exact description thereof, reference being had to the accompanying drawings, and to the letters of reference marked thereon, which form a part of this specification.

This invention relates to combined combs and curling-irons; and it consists in the features hereinafter set forth, and pointed out in 15 the claims.

Heretofore curling-irons of this class have been made of cast metal, having the teeth integral with the back. When so made, the teeth of the comb have been necessarily 20 very broad at the base, and after the teeth have been cut angles are left at their bases, which, with the straight bottoms of the cuts between the teeth, make the back other than cylindric and produce an unsymmetrical curl 25 of the hair.

A part of this improvement consists in making the comb-teeth of a separate thin plate of steel or other suitable metal set in a cylindric back, so that in the finished article the back is perfectly or substantially cylindric.

Another part of the invention consists in the mode of connecting the tooth-plate with the back, substantially as shown and herein- 35 after described.

In the accompanying drawings, Figure 1 is a perspective view of my improved comb and curler. Fig. 2 is a view of the comb-plate detached and having the teeth indicated by 40 dotted lines. Fig. 3 is a view of the comb-back viewed from the top side and before the blade or tooth-plate is inserted. Fig. 4 is a view of the under or inner side of the back before insertion of the tooth-plate, and Fig. 45 5 is a longitudinal central section of the completed implement through the channel which is cut in the cylindric back to receive the tooth-plate.

A represents the cylindric back of the com- 50 bined comb and curler, B the handle, and C the comb-teeth or tooth-plate. The back A

is preferably made from a solid steel rod drilled at one end to receive the handle B; but it may be a cylindric tube, if preferred. It is provided with a milled or otherwise 55 formed slot, a, to receive the comb-plate C, which slot, as illustrated, extends entirely through the cylinder A, forming the opening a'. (Seen in Figs. 3 and 4.) I have found that the slot a a' may be, on the whole, most eco- 60 nomically produced by means of a milling-tool having suitable diameter to give the desired length to the slot for the comb on the under or inner side of the back, while protruding centrally through the back to form 65 the opening a'. In the use of this size of milling-tool no relative longitudinal movement of the back or cylinder A need be made in cutting the slot; but, if preferred, a smaller milling-tool may be employed and a longitudinal motion given to the back in cutting 70 it to produce a slot of the desired length on the comb side of the back A, and the tool may be then forced through and out at the back of the cylinder A to give the opening 75 a'. Whatever the shape of the slot, however, it is desirable that the tooth-plate C shall essentially conform therewith, and it is therefore shown in Figs. 2 and 5 as having its back edge of the same curve as the periphery 80 of the larger milling-tool above referred to.

The comb-plate C protrudes through the opening a' at the top of the comb-back, as indicated in Fig. 5, which permits the same to be upset within the slot and then cut or 85 ground off to give a smooth and even surface with the top of the comb-back, as shown in Fig. 1. Thus secured, the comb-plate is not readily detachable from the back or cylinder A, notwithstanding its exposure to wide 90 changes of temperature in the legitimate use of the implement.

In Fig. 2 the teeth in the comb-plate C are indicated by dotted lines as yet uncut, but in Fig. 5 as being cut. The cutting of the teeth 95 will be performed before the plates are inserted, but they are cut to such a depth as to bring the bottoms of the notches substantially in line with the surface of the cylindric back A, as shown in Fig. 5. The tooth-plate C 100 therefore practically only fills the slot on the comb side or inner side of the back A, as it

does on the outer side thereof, and leaves the latter of practically cylindric form for best producing symmetrical curls of the hair. It is obvious, moreover, that by reason of the 5 comb-teeth being so thin at their base they leave a larger amount of unbroken cylindric surface on the part of the back A, which also contributes to the result desired. It is a still further advantage of making the tooth-10 plate C separate from the back and of sheet-steel or other firm metal that the teeth, while thin, are also strong, and therefore far less liable to break than would be the case if the teeth were of the cast-metal construction pre-15 viously employed.

The hole A', drilled in the end of the prolongation of the cylindric back A, to receive the handle B, is made, as shown in Fig. 5, much deeper than is necessary, to receive the 20 tenon on the handle, and in the unoccupied portion of said recess A' several holes, a², are drilled to ventilate the latter, so that the handle will not be heated or burned from heating the comb and its back. This, however, is a feature which is described in an 25 application for Letters Patent of the United States, Serial No. 291,342, filed on the 20th day of November, 1888, and is not here claimed.

30 While the mode of attaching the comb-plate C to the cylindric back A above illustrated and described is deemed preferable to

any other means for fastening the parts together, I do not wish to be restricted to the particular mode shown and described, since, 35 obviously, the slot may be so shallow as not to extend through the back, and through-rivets may be employed to hold the comb-plate in the back.

I claim as my invention—

1. A combined comb and curler consisting of a solid cylindric metal back provided with a longitudinal slot and a flat metal comb-plate inserted and immovably secured in said slot, with the inner ends of the slots or spaces 45 between its teeth substantially flush with the adjacent parts of the back, thereby forming a cylindric surface about which the hair may be wrapped in curling the same, substantially as described.

2. The combined comb and curler consisting of the metal cylinder A, provided with a through-slot, a a', and the comb-plate C, extending through the back in said slot and secured by a heading or lateral enlargement 55 at the opening a' of the back, substantially as described.

In testimony that I claim the foregoing as my invention I affix my signature in presence of two witnesses.

GEORGE L. THOMPSON.
